UNITED STATES PATENT OFFICE.

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS.

BELLOWS CONSTRUCTION.

Application filed May 10, 1924. Serial No. 712,177.

My invention relates broadly to bellows construction which has particular application to elastic piston pumps which effect the intake and discharge by the contraction and 5 expansion of the piston. Although I shall refer throughout the present case to this particular adaptation of my invention, it is to be understood that my invention has broader application and may be used wherever bellows 10 are needed for any purpose.

One aim of my invention is to provide an improved form of bellows construction having a life greatly in excess of bellows heretofore known.

15 The wall of an elastic piston in the above type of pump is usually in the form of an elastic membrane or bellows. The material of the wall undergoes alternating deformations at each stroke of the piston, which action 20 causes the material to become fatigued and hardened, and after a certain duration of operation, rupture of the piston is produced. This crystallization of the material which inevitably appears, causes a shorter life in the 25 piston, and is a considerable annoyance in practice.

An object of my invention is to construct the wall of the piston in such a manner that the deflection of the membrane or bellows, 30 and consequently the resultant strain, is placed upon a portion where practically no crystallization will occur. I accomplish this feature by dividing the bellows into separately formed sections, the edges of which are 35 bent in opposite directions to interlock alternately with the sections disposed above and below each section.

A further object of my invention is to provide a simple construction, which, in addition 40 to overcoming the difficulties of the prior art, may also be cheaply manufactured and be exceedingly efficient in its operation.

In order to apprise those skilled in the art how to practice and construct my invention, I 45 shall now describe an embodiment thereof in connection with the accompanying drawings.

In the drawings—

Figure 1 is a transverse cross sectional view 50 of a pump embodying my invention and illustrating a driving connection therefor in conventional form;

Fig. 2 is a perspective view of a section of the piston therein;

Fig. 3 is a similar view of another section

which cooperates with the first section for 55 building up the flexible wall of the piston;

Fig. 4 is a cross sectional view taken on line 4—4 of Fig. 2;

Fig. 5 is a similar view taken on line 5—5 of Fig. 3; and,

Fig. 6 is an enlarged vertical sectional view through several of these sections in inverted position to illustrate the manner of assembling the same.

The pump 1, as shown in Fig. 1 and which I have chosen to illustrate my invention in one of its preferred forms, comprises an open cylinder 2 which is closed at its open end by means of a suitable plate 3. In this plate 3 the intake and the outlet valves (not shown) 70 are disposed in any suitable manner, depending, of course, on the use to which this pump is put.

Within cylinder 2 a diaphragm piston member 4 is adapted to actuate. The wall of 75 piston member 4 is preferably in the form of an elastic membrane or bellows and is built up of a plurality of units 5, each of which comprises an upper and a lower section 6 and 7, respectively. The circumferential upper 80 edge of piston 4 is rigidly attached to plate 3, and consequently, the piston at this end is held against movement.

The present application is a continuation 85 of my copending application, Serial No. 641,669, filed May 26, 1923, in so far as the disclosure of the elastic pump in my copending application is concerned. In this prior application, a rigid connection with a piston is illustrated, thereby causing the piston to 90 assume a slight transverse movement, as well as a longitudinal movement when actuated. The advantage of this form of drive is apparent.

It permits a closer association of the driving elements and allows the piston to be 95 used in a place where a flexible joint between the piston rod and the piston itself would be prohibited. In the present case, this rigid connection comprises a piston rod 8 extending through an aperture 9 and into the interior of piston 4, rigidly connecting at 10 to plate 11, which forms the head of the piston. Connecting rod 8 pivotally connects to an eccentric 12 disposed on a worm gear 13. Worm gear 13 is driven by a worm 14, which 105 may be carried on a motor shaft 15, or any other suitable shaft. From this description it will be seen that the drive by which piston 4

is driven is simple and the parts of the same may be assembled in compact relation.

As before mentioned, the piston 4 is constructed to resemble a bellows. This bellows 5 is built up by the units 5, and consequently, the piston 4 may be conveniently made in any desired length without the additional expense of different machines or tools. Units 10 are of standard construction and may be carried in stock to permit the construction of pistons of any desired size. Each unit 15 comprises the sections 6 and 7, which in blank form comprise apertured sheet metal plates or rings. The sections are preferably stamped in two operations. In Fig. 3, the upper section is illustrated as provided with an inner circumferential upstanding flange 17 which is joined to the flat horizontal portion 18 by a curved portion 19. At the outer 20 edge the material of the section is turned upwardly slightly at 20 and then over and downwardly again to result in a circumferential flange 21 and a circumferential groove or gutter 22. The lower section 7 may be formed 25 with an outer circumferential upstanding flange 24, the edge of which is adapted to enter the gutter 22 in the upper section 6. The inner edge of section 7 may be provided with a downwardly extending flange 25, 30 which permits the formation of a groove or gutter 26. The flange 25 is preferably curved away from the flat horizontal portion 27 at a smaller angle than the flange 24. A curved portion 28, which joins the flange 24 and horizontal portion 27 of section 7, forms the point about which the inner part of section 35 7 may flex. The same is true with respect to the curved portion 19 of the upper section. Here the outer part of section 6 is allowed to 40 flex about the curved portion 19. The purpose of this arrangement will be presently described. In assembling sections 6 and 7, the flange 24 of the lower section is adapted to enter the circumferential gutter 22 of the 45 upper section 5, which the flange 17 of the upper section is adapted to enter the circumferential gutter at 26 of the lower section 7 of the preceding unit 5.

In Fig. 6 I have illustrated the method of 50 assembling the sections 6 and 7. The upper section 7 is first inverted and solder 30 is poured in the circumferential gutter 26. The lower section 6 is also then inverted and superimposed upon section 7 so that flange 55 17 will enter the solder 30 and seat within the gutter 26. Solder is then poured in gutter 22 of section 6 and the next lower section 7 is inverted so that its outer circumferential flange 24 will enter the solder and 60 also seat in the gutter 22. As soon as solder 65 30 is set, the various sections 6 and 7 are rigidly united. I wish to point out when flanges 17 and 24 enter gutters 26 and 22, respectively, there is a tendency for the solder to rise on the interior walls of the sec-

tions 6 and 7, as indicated at 31, which incidentally permits a secure joint to be obtained at these points. These joints permit lubricant to be fed to the interior of piston 4 without escaping to the interior of cylinder 70 2. As before set out, this construction of the bellows tends to prevent hardening or crystallization of the metal, and consequently, the life of the bellows is greatly prolonged. It is to be remembered that if the 75 metal crystallizes, cracks through which the lubricant may leak are apt to appear. The construction illustrated permits the bellows to be made of any size without additional expense in the form of extra machinery or 80 tools and besides provides a more durable arrangement without sacrificing in the flexibility of the piston wall. On the contrary, the bellows wall has a greater flexibility and the joints are not weakened by the transverse 85 movement of the bellows which results from the rigid connection 10 with the piston rod 8. I find that the diaphragm piston member 4 will function with greater efficiency when assembled of the sections 6 and 7 in the 90 manner disclosed than when the wall is made integral and corrugated, as was heretofore done in the prior art.

While I have disclosed the present invention embodied in a piston, it is to be understood that the bellows shown in the drawings may be used wherever desired and for any purpose, without departing from the scope of this invention.

Without further elaboration, the foregoing will so fully explain the gist of my invention, that others may, by applying current knowledge, readily adapt the same for use under varying conditions of service, without eliminating certain features which 100 may properly be said to constitute the essential items of novelty involved, which items are intended to be defined and secured to me by the following claims.

I claim:

1. A bellows construction of the type described having its side wall divided into a plurality of sectional parts, each of which is fastened to the sections above and below by a circumferential edge engagement, said engagement comprising a gutter in one of the engaging sections and a cooperating flange on the other engaging section.

2. A bellows construction of the type described having its side wall divided into a plurality of sectional parts, each of which engages the sections above and below, said engagement comprising a gutter in one of the engaging sections and a cooperating flange on the other engaging section.

3. A bellows construction of the type described having its side wall divided into a plurality of sectional parts, each of which is fastened to the sections above and below, and is provided with a solder filled gutter

for the reception of a flange on one of the adjacent sections.

4. An expandible tube comprising a plurality of annular metallic disks arranged in pairs and secured successively to each other, the disks of each pair being provided with gutters, located alternately, substantially at the peripheries and substantially at the interior edges, to receive a flange on the adjacent disk of the same pair or flanges on the disks of adjacent pairs, said gutters receiving molten solder into which said flanges are inserted during the assembly, said molten solder rising on the walls of said flanges when inserted, forming a substantial hermetic union between the disks when the solder hardens, said gutters and said flanges being arranged or formed on said disks so as to practically eliminate deflection and prevent crystallization of the metal at or near the union of said disks.

5. An expandible tube comprising a plurality of annular metallic disks arranged in pairs and secured successively to each other, each of said disks being provided with a gutter and an upturned flange, located alternately either substantially at the periphery or substantially at the interior edge, the gutters and flanges of the disks of each pair and of adjoining pairs being alternately located so as to engage the flange of a disk in the gutter of an adjacent disk, and means for hermetically uniting the union formed by the engagement of the respective flanges and gutters.

35 6. An expandible tube comprising a plurality of annular metallic disks arranged in pairs and secured successively to each other, each of said disks being provided with a downturned gutter and an upturned flange, located alternately, either substantially at the periphery or substantially at the interior edge, the gutters and flanges extending from the main plane of said disks at a substantial angle by means of curved portions integral therewith, the curved portions adjacent said flanges being curved slightly greater than the curved portions adjacent said gutters, preferably to permit the bending movement of said disks to occur mainly at these portions of greater curve, said upturned flanges entering said downturned gutters, solder for holding said flanges in said gutters, the union formed being free of bending strains resulting from said bending movement, the formation of said portions of greater curve at a point between said flanges and the main plane of said disks tending to minimize all crystallizing effects upon said disks due to said bending movement.

60 7. An expandible element comprising a plurality of annular metallic disks arranged in pairs and secured successively to each other to form a fluid tight seal, said disks being provided at their peripheries and at their interior edges with means for forming a seam

between the adjacent disks, said disks each having a curved portion, alternately located, either at the periphery or the inner edge to increase the flexibility and to localize the bending movement of each disk substantially at said curved portion, thereby preventing a bending strain where said disks are joined and minimizing the crystallization of the metal elsewhere in said disks.

8. An expandible element comprising a plurality of annular metallic disks arranged in pairs and secured successively to each other, said disks being provided at their peripheries and at their interior edges with means for forming a union between the adjacent disks, said disks each having a portion tending to increase the flexibility and to minimize the crystallization of said disks, and to prevent any bending movement or bending strain at or near said disks where united by said means.

9. A bellows construction having its wall divided into a plurality of sectional parts, and means for uniting said sectional parts together in a manner to prevent weakening of the wall at the union as the result of repeated flexing of said sectional parts.

10. A bellows construction divided into a plurality of sectional parts so united with each other as to prevent weakening of the material at the union.

11. A bellows construction divided into sectional parts and secured successively to each other, said parts each being of cup formation and having a flat portion with the edges thereof turned so mounted as to confine the deflection of each part to its flat portion.

12. An article of manufacture comprising bellows sections, each section being of cup formation having a flat portion provided with side walls of cylindrical or conical shape so mounted as to stiffen said walls and confine the deflection of each section to its flat portion.

110 13. A bellows construction comprising a plurality of sections arranged in nested relation and having the inner and outer edges thereof provided with upstanding flanges adapted to be joined to the flanges of adjacent sections.

14. A bellows construction comprising a plurality of sections provided with inner and outer flanges, all being arranged substantially in the same general direction, said sections being nested one within the other and the flanges of one section joining the flanges of adjacent sections.

125 15. A bellows construction comprising a plurality of sections, flanges formed on the inner and outer edges of said sections and arranged to permit said sections to nest one within the other, the flanges of each section joining the flanges of adjacent sections disposed above and below.

16. A bellows construction comprising alternating sections, one having an inner gutter and an outer flange, and the other having an outer gutter and an inner flange, and 5 means for fastening the alternating flanges in the alternating gutters. 17. An expandable and collapsible element comprising sectional parts which are joined at their periphery by a gutter on one of the 10 sections and a cooperating flange on the other section. 18. An expandable and collapsible element comprising sectional parts which are joined together by a gutter on one of said sections 15 and a peripheral flange on the other section. 19. An expandable and collapsible element comprising sectional parts secured to each other, each flexible section having a flat portion with the edges thereof turned in the same 20 direction whereby to confine the deflection to said flat portion. 20. An expandable and collapsible element comprising a flexible sectional part secured to an adjacent sectional part, said flexible section 25 having a peripheral flange secured in a gutter in said adjacent section. 21. An expandable and collapsible element comprising sectional parts jointed together at their peripheries by a soldered joint, said joint comprising a gutter in one section, solder in said gutter, and the edge of the other section extending into said gutter and imbedded in the solder. 30 22. An expandable and collapsible element comprising sectional parts joined together at 35 their peripheries by a soldered joint, said joint comprising an open top gutter in one section, solder in said gutter, and the peripheral edge of the other section extending into said gutter and imbedded in the solder. 40 23. An expandable and collapsible element comprising sectional parts joined together at their peripheries by a soldered joint, said joint comprising a V-shaped gutter, solder in the gutter, and the peripheral edge of the 45 other section seated in said gutter and imbedded in the solder. 24. An expandable and collapsible element comprising sectional parts joined together at their peripheries by a soldered joint, said 50 joint comprising a gutter in one section, solder in said gutter, the peripheral edge of the other section extending into said gutter and embedded in the solder, the solder rising upwardly of the side faces of the imbedded edge. 55

In witness whereof, I have hereunto subscribed my name.

LAWRENCE M. PERSONS.
